R. TAYLOR

COMBING MACHINE

Filed Nov. 17, 1920

FIG. 2.

INVENTOR:

By Robert Taylor
Wm Wallace White
ATTY.

Patented Mar. 3, 1925.

UNITED STATES PATENT OFFICE.

ROBERT TAYLOR, OF OLDHAM, ENGLAND.

COMBING MACHINE.

Application filed November 17, 1920. Serial No. 424,633.

To all whom it may concern:

Be it known that I, ROBERT TAYLOR, a subject of the King of Great Britain, residing at Soho Iron Works, Oldham, in the county of Lancaster, England, have invented new and useful Improvements in Combing Machines, of which the following is a specification.

My invention relates to improvements in those combing machines which have attached a pneumatic appliance such as the aspirator described in the specification of the patent to Roth #905,233 dated December 1, 1908, for removing the waste from the cylinder brushes.

In connection with combing machines having such pneumatic appliances I have ascertained that a fault occurs in the combed web immediately after re-starting the machine after a stoppage for meals or for piecing up or for other purpose. This fault arises from the fact that although the combing parts of the machine start up immediately the driving strap is put on the fast pulley in spite of some slippage that may occur between the strap and the pulley yet the fan or aspirator does not attain an effective speed so quickly with the result that the brush and the combing cylinder are imperfectly stripped and cleaned and some of the waste is imparted to and carried forward by the web.

The object of my invention is to obviate this fault or defect, and I attain this object by attaching a pulley to the loose pulley and driving the fan or aspirator therefrom instead of from the fast pulley, and arranging that when the combing machine is running the driving strap shall be partly on the loose pulley which continues to run when the driving strap is on the fast pulley, thus the fan or aspirator continues to run when the machine is stopped and is at full working speed the moment the machine is re-started.

Further, I may or may not provide an adjustable stop to prevent the driving strap being moved entirely off the loose pulley, and this stop can be moved out of the way, for any purpose, when it is desired to stop the loose pulley.

I illustrate an embodiment of my invention in the accompanying sheet of drawings, in which—

Fig. 1 is an elevation of the driving end

of a combing machine to which my invention is applied and Fig. 2 is an end elevation of the same.

In these views *a* designates the frame of the driving end of the combing machine; *b b* pedestals and *c* a bearing which support the driving shaft *d* with its loose pulley *e* and fast pulley *f*.

For the purposes of my invention I form or combine as one with the loose pulley *e*, an additional pulley, in this case, a grooved pulley *e'*, and I connect this pulley by a V strap or rope *g* to a similar pulley *h'* fixed on the shaft *h* of the fan or aspirator. The driving strap *i* is wide enough to completely cover the fast pulley *f* and also to overlap the loose pulley *e* so that whether the strap *i* is on the fast pulley *f* or the loose pulley *e* motion is constantly transmitted from the pulley *e'* by the strap or rope *g* to the pulley *h'*, the shaft *h* and so to the fan or aspirator.

In this arrangement there is no delay or possibility of the fan or aspirator lagging behind in the re-starting of the combing mechanism as the fan or aspirator is always running whether the driving strap *i* be on the fast or the loose pulley.

The adjustable stop above mentioned when employed may be of any suitable type arranged in any convenient manner, as for example, a part formed or secured on the usual stop rod and a piece hinged to the framing which may be put in the path of the part on the stop rod and so limit its movement.

What I claim as my invention and desire to secure by Letters Patent of the United States is:—

In a combing machine, the combination of a shaft having fast and loose pulleys mounted thereon, a third pulley affixed to said loose pulley and rotated thereby, a belt for driving said fast and loose pulleys, said fast pulley being of less width than the belt, a fan shaft adapted to be driven by said third pulley, and means for shifting said belt to start and stop the machine whereby the fan shaft will be operated regardless of whether or not the machine is in operation.

In testimony whereof I have signed my name to this specification.

ROBERT TAYLOR.

Witness:
HERBERT ROWLAND ABBEY.
